[57] CLAIM

The ornamental design for a carton holder, as shown and described.

DESCRIPTION

FIG. 1 is a top perspective view of a carton holder showing my new design;

FIG. 2 is a side elevational view thereof;

FIG. 3 is a front elevational view thereof;

FIG. 4 is a rear elevational view thereof;

FIG. 5 is a side elevational view opposite that shown in

FIG. 2;

FIG. 6 is a top plan view thereof; and

FIG. 7 is a bottom plan view thereof.
